UNITED STATES PATENT OFFICE.

SYDNEY CARROLL WENTZ, OF SPRING GROVE, PENNSYLVANIA, ASSIGNOR, BY MESNE ASSIGNMENTS, TO PAPER MACHINERY CORPORATION, OF DAYTON, OHIO, A CORPORATION OF OHIO.

PAPER-MAKING MACHINE.

Application filed April 12, 1926. Serial No. 101,375.

My present invention relates to improvements in paper machines of the Fourdrinier type, and particularly to the means in co-action with the wire for forming the deckle 5 edge of the paper.

The invention contemplates an attachment for paper making machines which is simple in construction and operation; which may be installed on the machine with facility and a 10 minimum expenditure of labor, and which may be adjusted with accuracy and convenience to co-act with the wire in the formation of the deckle edges of the paper-web. The invention consists in certain novel combinations 15 and arrangements of parts in connection with stationary edge guides or rulers located at the sides of the web whereby the movement of the web may be controlled and the deckle edges properly fashioned, as will 20 hereinafter be more fully set forth and claimed.

The present invention is in some respects analogous to that disclosed in the copending application of Sydney C. Wentz, Serial No. 25 72,561, filed December 1, 1925, for paper making machine, which has developed into Patent 1,603,226 dated October 12, 1926.

In the accompanying drawings I have illustrated one complete example of the physical embodiment of my invention wherein the parts are combined and arranged in accordance with one mode I have devised for the practical application of the principles of my invention.

Figure 1 is a view at one side of a paper machine showing an end of one of the decking devices, it being understood that an oppositely arranged decking device is used at the opposite side of the machine, for forming 40 the decking edges.

Figure 2 is a transverse vertical sectional view at line 2—2 of Figure 1.

Figure 3 is a view in elevation at the outer side of one of the duplicate decking devices, 45 showing it supported on a side rail or part of the stationary frame of the machine.

Figure 4 is an enlarged detail vertical sectional view at line 4—4 of Figure 3.

Figure 5 is an enlarged detail view.

Figure 6 is a detail view showing one of the edge-guide or ruler supports.

The device of my invention may readily be attached to machines now in use and substituted for the usual endless deckle belts or 55 guides located at the sides of the machine

above the wire, or the device may with greater facility be incorporated as part of the paper machine in its process of manufacture.

The decking devices are located at opposite sides of the machine, extending longitudinally thereof, and are supported on the side rails 1 at the upper longitudinal edges of the machine frame in proximity to the wire screen or endless apron 2, which travels over the brass table rollers 3 as usual. These 60 rolls or rollers extend transversely of the machine and support the working flight of the endless apron or wire which travels longitudinally of the machine. The web is indicated at 4 in Figure 1 as being fashioned on 70 the screen or wire apron, and at each side of the web a decking device is located similar to that shown in Figures 1 and 3.

The deckle frame which supports the assembled parts of my invention directly over 75 the lateral edges of the wire, includes a pair of longitudinally extending side plates 5 (only one of which is shown herein) and this plate is supported from its complementary side rail 1 of the machine by means of a 80 pair of horizontal bars 6 and 7 which extend transversely of the machine and pass through openings near the respective ends of the side plates 5.

The supporting bars 6 and 7 as shown are 85 preferably of tubular construction to insure lightness of weight with strength, and each bar is rigidly supported in a block, as 8 and 9, spaced apart and each provided with a split portion 10 and clamping bolt 11 by 90 means of which the respective bars are clamped in their blocks.

Thus when the bolts 11 are loosened the bars may be adjusted transversely of the machine in their clamp blocks to desired position, and then the blocks and bars are rigidly clamped together by means of the bolts. Each block has a base plate or flange 12 with bolt slots 13 therein, and preferably four bolts 14 are passed up through bolt holes in the side 100 rail and the bolt slots of the flange, and nuts 15 are used to clamp the flange to the rail.

As best seen in Figure 1 each clamp block is fashioned with a fulcrum edge or rib 16, which may be formed by beveling the under-side of the base plate or flange 12 in opposite directions, and this edge, which extends longitudinally of the machine, forms the sole contact between the deckle frame and the side rail of the machine. Thus it will be 110

apparent that by manipulating the four nuts of the bolts 14 the blocks may be tilted on their fulcrum edges to desired position for swinging the bars and side plate to adjust the 5 deckling device with relation to the wire. This swinging movement, which is slight, permits facility and insures accuracy in the adjustment of the deckle frame, and when the nuts 15 are tightened the frame is held in 10 rigid relation to the machine frame or side rail 1.

The side plates 5 of the deckle frame are adjustable laterally of the machine or wire, on the bars 6 and 7, and for this purpose, at 15 their ends, the side plates are provided with attaching plates as 17 and 18, bolted at 19 to the outer face of the side plate. Each attaching plate is formed with a collar 20 and a set screw or bolt 21 is threaded in a bush- 20 ing 22 of the collar to frictionally engage the periphery of the bar and thus retain the side plate on the bar in adjusted, rigid relation thereto. By this means the side plate may accurately be adjusted laterally of the 25 machine over the edge of the wire or apron, and the adjusted parts made rigid in their relation by means of the screws or bolts 21 in the bosses 22.

At its lower edge the side plate 5 is fashioned with a retaining flange 23 for the rubber edge-guide or ruler 24 and these elements, which are disposed at approximately an angle of 45 degrees to the side plate, lie in position with the bent lower edge of the rubber 30 ruler upon the top face of the wire or apron, for the purpose of forming the deckle edge on the paper.

The rubber edge ruler is pressed against 40 and held to the outer face of the retaining flange by means of a retaining bar 25 which extends longitudinally of the retaining flange the full length of the ruler, and frictionally engages the outer face of the ruler. As the 45 lower working edge of the rubber ruler wears away due to frictional contact therewith of the wire, the ruler may gradually be adjusted and lowered to compensate for the wear.

The retaining plate is fashioned with a longitudinally extending tongue or rib 26, and a 50 series of resiliently pressed levers 27, each pivoted as at 28 in a bracket 29 screwed to the outer face of the retaining flange, is provided to retain the ruler against the face of the retaining flange. At their lower ends 55 the levers are fashioned with grooved heads 30 which fit over the rib of the retaining plate to support the plate and press it against the ruler. The levers, which are located at the outer side of the deckle frame, but within 60 the side rails of the paper machine, extend vertically upwardly above the side plate. They are spaced apart at suitable intervals and their number may be varied if desired. At their upper ends the levers are provided 65 with vertical slots 31 to receive or surround

the free ends of a set of fixed screws 32 which project outwardly from the deckle frame and are secured by lock nuts as 33 to posts 34 of the side plate. Between the slotted arm of the lever and the side plate a traveling nut 70 35 and a spring 36 are located. The spring is coiled about the screw or threaded bar and interposed between the nut and the slotted lever arm, and it will be apparent that by turning the nut the tension of the spring 75 may be varied. The spring exerts its tension against the lever arm to press the retaining plate against the ruler and retaining flange of the side plate to rigidly hold the flexible, resilient ruler in position. 80

Various changes may be made in the combinations and arrangement of parts as herein shown, within the scope of my claims, without departing from the spirit of my invention, as it will be understood that the exemplified 85 structure is capable of alterations and adaptations to convert it for use under varying conditions in existing machines.

Having thus fully described my invention, what I claim as new and desire to secure by 90 Letters Patent is—

1. The combination with a deckle frame including a side plate and a ruler supported therefrom, of transversely disposed supports for said plate, a frame, tilttable blocks for said 95 supports fulcrumed on said frame, and means positioned on opposite sides of the fulcrum for fastening each of said blocks in adjusted position.

2. The combination in a deckle frame with 100 a side plate having a retaining flange and a ruler, of a retaining plate for the ruler, retaining levers pivoted on the retaining flange and engaging the retaining plate, and resilient means supported on the side plate and 105 bearing against said levers for pressing the levers against the retaining plate.

3. In a paper making machine, a forming wire, a longitudinally extending stationary deckle member to limit the lateral spread of 110 stock upon said wire, a deckle frame for supporting said deckle member, a side rail, a 115 tiltably mounted member carried by said side rail, said tiltably mounted member having a knife-edge bearing on said side rail, and a transversely extending support for said deckle frame carried by said tiltably mounted member.

4. In a paper making machine, a forming wire, a longitudinally extending stationary 120 deckle member to limit the lateral spread of stock upon said wire, a deckle frame for supporting said deckle member, a side rail, a tiltably mounted block fulcrumed on said side rail, adjusting bolts for fastening said block to said side rail, a transversely extending support carried by said block, said support slidably receiving and supporting said deckle frame thereon to permit lateral adjustment of said deckle member relative to 125 130

the wire, and means for clamping said deckle frame in adjusted position on said transversely extending support.

5. Stationary deckle means for a paper making machine, comprising a longitudinally extending side plate, a retaining plate, a deckle member frictionally engaged between said plates, a lever pivotally mounted intermediate its length on said side plate and engaging said retaining plate, a spring interposed between said side plate and said lever on the opposite side of said pivot from the retaining plate for urging said lever and retaining plate toward said side plate and interposed deckle member, and means for adjusting the urging force of said spring.

6. Stationary deckle means for a paper-making machine, comprising a longitudinally extending side plate, a retaining plate, a deckle member frictionally engaged between 20 said plates, a lever pivotally mounted intermediate its length on said side plate and engaging said retaining plate, a member carried by said side plate and extending through an opening in said lever, a spring surrounding said member and interposed between said side plate and said lever for urging said lever and retaining plate toward said side plate and interposed deckle member.

In testimony whereof I hereunto affix my 30 signature.

SYDNEY CARROLL WENTZ.
